Nelwood W. Howard

UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

LAST.

Application filed July 22, 1927. Serial No. 207,694.

This invention relates to lasts and particularly to lasts shaped to facilitate the desired formation of the bottoms of shoes in the laying and leveling operations.

5 One object of the invention is to provide a last by the use of which, in the laying and leveling operations, a close shank will be produced; that is, the margin of the sole at the shank will be bent toward the upper so that 10 the top face of the sole or the welt, if the shoe is a welt shoe, will be brought into contact with the upper and the welt crease closed.

Another object of the invention is to provide a last such that filling material at the 15 forepart may be substantially dispensed with, only a very thin filler, if any, being required, and such that the inner surface of the sole may be given a conformation better adapted to the shape of the foot.

20 With these objects in view, one feature of the invention consists in a last the shank portion of which has a surface to support the shank portion of the insole, which preferably has the usual transverse and longitudinal 25 curvature but which, outside of the area covered by the insole at each side thereof, affords no support for the upper, the surface dropping away abruptly at the edge of the insole and meeting the usual contour of the sides of 30 the shank of the last along a line disposed outwardly beyond the line of the edge of the outsole and welt, if the shoe is a welt shoe. The pressure of an inclined leveling roll or other 35 laying or leveling instrument upon the margin of the outsole laid upon the last of the present invention can therefore bend the sole farther than it can when the last is of the usual construction because the portion of the upper against which the margin of the sole 40 is pressed in unsupported by the last. As illustrated, a rebate is formed in the last along the shank portion and outwardly beyond the portion covered by the insole.

Another feature of the invention consists 45 in a last the margin of the forepart of which is inclined upwardly and outwardly, regarding the last in the normal position of the foot; that is, the margin is inclined outwardly and toward the body of the last and 50 is substantially coextensive with that portion of the insole which lies outwardly of the inner edge of the inseam. In making a shoe on such a last, the inseam and margin of the forepart

of the insole are made to occupy the space provided by the inclination of the marginal surface of the last bottom, and the area outlined by the insole rib requires little or no filler to bring its surface flush with the inseam and welt and parallel to the inner surface of the outsole.

55 In modern shoemaking it is frequently desired that the outsole be transversely flat and that the surface of the insole on which the central portion of the forepart of the foot rests be also flat. Accordingly, as illustrated, the area of the forepart of the last within the inclined marginal portion is flat transversely, the inclined margin taking care of the extra thickness of the shoe materials in the vicinity of the inseam and allowing the welt and the top of the sewing lip to lie transversely in a straight line corresponding to the position the inner face of the outsole is to assume.

50 In the drawings,

Fig. 1 is a perspective view of a last embodying the present invention;

Fig. 2 is a transverse section through the forepart of a shoe on the last of Fig. 1;

Fig. 3 is a transverse section through the shank portion of the shoe and last, showing the action of a leveling roll on the shank portion of the shoe; and

Fig. 4 and 5 are views, similar respectively to Figs. 2 and 3, of a shoe and last of the usual construction.

70 In Fig. 1 is shown a last having the usual construction in its body and heel-seat portions. From the heel-breast line 10 to the ball line 12 the bottom of the shank portion 14 of the last is transversely and longitudinally curved, as usual, throughout the area covered by the insole, that is, between the lines 16 and 18. From these lines outwardly, however, the last is cut away or rebated, the surface of the cut-away portion forming a reentrant angle the outer side of which merges into the usual surface of the side of the last along the line 20 on the outer side and along the line 22 on the inner side, the line 20 extending from adjacent to the ball line to a point somewhat at the rear of the breast line, and the line 22 having a similar extent on the inner side of the last.

75 80 85 90 95 100 105 As illustrated, the surface of the shank portion 14 at the lines 16, 18 drops off abruptly

substantially perpendicularly to the portion 14 and then extends outwardly substantially parallel to the insole but spaced therefrom by the height of the perpendicular portion 5 until it merges into the side surface of the last, a reentrant angle being formed along the line 24 between the perpendicular portion and the outwardly extending portion and the width of the perpendicular portion and the 10 outwardly extending portion becoming less and less from the central portion of the shank toward the breast line 10 and toward the ball line 12. It will be noted that the reentrant angle or groove formed by the perpendicular 15 portion and the outwardly extended portion is formed in that portion of the last which is normally bridged by the marginal portion of the lasted upper in extending from the side of the last over the feather of the insole, as illustrated at the left of Fig. 5, and that this 20 formation of the last does not affect the function of the last in determining the shape of the lasted upper, the reentrant angle or groove being located inwardly of the last bottom. 25 with respect to the surfaces of the last which impart shape to the shank portion of the upper. The rebate or space provided by forming the shank portion of the last in the manner described is bridged by the lasted upper 30 and lining 25, as shown at the left of Fig. 3, and enables the pressure of a laying or leveling implement such as a roll 26, as shown at the right of Fig. 3, to force the upper into this space as it acts to bend the margin of the 35 sole and the welt toward the last. Thus, resistance to such bending of the sole, as presented by the usual last (Fig. 5) is removed and the margin of the sole may be bent into the rebate beyond the position it is desired 40 that it shall assume in the finished shoe, with the result that the sole will remain sufficiently bent to cause the welt to remain permanently in engagement with the upper with the welt crease closed. 45 The central portion 30 of the forepart of the last is transversely flat and may, as demanded by some styles of modern shoes, be longitudinally flat also. The area of the projection of the upper-shaping surface of the 50 forepart upon the plane of the last bottom is substantially equal to the area of the bottom of the forepart. The margin 32 of the last bottom outside of the flat area 30 is sloped or inclined outwardly and toward the body 55 of the last; that is, the margin of the bottom of the forepart from one end of the ball line about the forepart to the other end of the ball line is inclined heightwise of the last away from the plane of the central portion, the 60 heightwise displacement of the margin at the edge of the last being substantially less than the widthwise extent of the inclined margin. At the ball line the ends of the inclined margin merge into the surface of the shank portion 14 65 without definite lines of demarcation. The width and inclination of the margin of the last are so proportioned with respect to the insole being used that the inclined margin is substantially coextensive with that portion of the insole which lies outwardly of the inner edge 70 of the inseam; therefore, enough extra space between the last bottom and the outsole is provided to accommodate the inseam after the inseam trimming operation, that is, space to receive the rib of the insole, the edge of the lasted upper and the margin of the welt held together by the stitches 34. This construction obviates the necessity of using any substantial amount of filling material to prepare the shoe bottom for the reception of an outsole 80 36, as shown in Fig. 2. In this view a very thin filler 38 is shown, but it is to be understood that by slightly increasing the heightwise inclination or widthwise extent, or both, of the margin 32, the filler 38 may be dispensed with entirely. The conditions obtaining in the use of a last embodying the present invention are clearly illustrated in Fig. 2, and, in contrast to this, Fig. 4 shows the conditions 85 of manufacture of a shoe on a last of usual construction in which a relatively large amount of filling material is necessary to prepare the shoe bottom for the reception of an outsole. It is to be understood, of course, that a thick layer of filler is objectionable as it is 90 apt, under pressure of the foot, to become displaced and bunched up, causing discomfort to the wearer; also that a heavy filler detracts from the lightness and flexibility of the shoe and is otherwise objectionable. The 95 raising of the margin of the insole of a shoe made on the last of the present invention is an advantage, as the insole then conforms more closely to the contour of the foot and prevents sidewise slipping of the foot and consequent distortion of the shoe upper and loss of the shapeliness imparted to it in the 100 lasting operation.

Having thus described my invention, what I claim as new and desire to secure by Letters 110 Patent of the United States is:

1. A last having an angular rebate along the shank portion of sufficient depth to permit bending of the margin of the shank portion of the outsole of a shoe on the last to, or beyond the plane of, the inner surface of the insole. 115
2. A last having an angular rebate of substantial depth along the shank portion to permit bending of the margin of the outsole of a shoe on the last to, or beyond the plane of, the inner surface of the insole, said rebate narrowing toward the ball line and the heel-breast line. 120
3. A last for shoes having the shank portion outside the area covered by the insole formed with a reentrant angle of substantial depth into which the margin of the outsole and upper of a shoe on the last may be forced by a leveling instrument to form a tight 125 130

joint between the upper and the bottoming materials.

4. A last having a reentrant angular rebate of substantial depth along the shank portion to permit bending of the margin of the outsole of a shoe on the last toward the inner surface of the insole, said rebate narrowing toward and disappearing at the ball line and narrowing toward and disappearing at a point slightly beyond the breast line.

5. A last for shoes having the shank portion at each side of the area covered by the insole of a shoe on the last and within the area bridged by marginal portions of the 15 lasted upper extending from the side of the last over the feather of the insole formed as a reentrant angle at least as deep as the thickness of the feather of the insole.

6. A last for shoes having at each side of 20 the shank portion beyond the area covered by the insole of a shoe on the last a reentrant groove of sufficient depth to prevent opposition by the last to shank forming pressure applied to the margin of the outsole of the 25 shoe.

7. A last for welt shoes having the part of its shank portion covered by the insole of a shoe on the last of the usual transverse and longitudinal curvature, the portion of the 30 shank portion only of the last beyond the edges of the insole being formed with an angular rebate to permit bending toward the last of the shank portions of the sole and welt, which project beyond the edges of the insole.

35 8. A last having the shank portions only of the surface of the last outside of the edges of the insole of a shoe on the last formed to present a wall of substantial height perpendicular to the plane of the insole and an outwardly extending surface parallel to the insole and spaced therefrom by the height of said wall heightwise of and toward the body of the last.

40 9. A last for welt shoes having the margin 45 of its forepart beveled to provide a space to be occupied by the inseam so that an outsole can be applied in a flat condition and substantially without the use of filling material and having the shank portion at each side of 50 the area covered by the insole cut away to provide a space into which the margins of

the outsole and welt may be bent to form a close shank.

10. A last for welt shoes having the margin of its forepart inclined outwardly and 55 toward the body of the last and having the shank portion at each side of the area covered by the insole of a shoe on the last cut away to facilitate the formation of a close shank.

11. A last for welt shoes having the margin of its forepart only inclined outwardly and toward the body of the last, the widthwise extent of said inclined margin being greater than the heightwise displacement of its outer edge, said inclined margin being 60 substantially coextensive with that portion of the insole which lies outwardly of the inner edge of the inseam.

12. A last for welt shoes having the interior of its forepart transversely flat and 70 the margin of its forepart inclined outwardly and toward the body of the last, the extent of the inclined margin being sufficiently wide to underlie the inseam of a shoe upon the last and having at each side of the shank portion 75 beyond the area covered by the insole of the shoe on the last a reentrant space of sufficient depth to permit the formation of a close shank by application of pressure to the margins of the outsole and welt to force them into the 80 space.

13. A last for shoes having the area of the projection of the upper-shaping surface of the forepart upon the plane of the last bottom substantially equal to the area of the 85 bottom of the forepart and having a groove of substantial depth along the shank portion at each side of the last located outwardly with respect to the area of the last bottom covered by the shank portion of the insole and inwardly with respect to the surfaces of the last which imparts its shape to the shank portion of the upper, said groove narrowing toward the ball line of the last and permitting the margins of the outsole to be forced 90 toward the last without opposition by the last to facilitate the formation of a close shank.

In testimony whereof I have signed my name to this specification.

ERASTUS E. WINKLEY.
